(57) **CLAIM**

The ornamental design for an electric powered personal transport vehicle, as shown and described.

DESCRIPTION

FIG. 1 is a top perspective view of an electric powered personal transport vehicle;

FIG. 2 is a bottom up perspective view of an electric powered personal transport vehicle;

FIG. 3 is a side view of a first side of an electric powered personal transport vehicle;

FIG. 4 is a side view of a second side of an electric powered personal transport vehicle;

FIG. 5 is a top down view of an electric powered personal transport vehicle;

FIG. 6 is a bottom up view of an electric powered personal transport vehicle;

FIG. 7 is a rear view of a first end of an electric powered personal transport vehicle; and,

FIG. 8 is a front view of a second end of an electric powered personal transport vehicle.

The broken lines showing the electric powered personal transport vehicle in FIGS. 1-8 are for the purpose of illustrating portions of the article that form no part of the claim. The radiating dot-dash lines illustrate the glow of an illuminated portion of the electric powered personal transport vehicle, and forms no part of the claimed design.

1 Claim, 7 Drawing Sheets
